(57) CLAIM

The ornamental design for a bag as shown and described.

DESCRIPTION

The file of this patent contains at least one drawing/photograph executed in color. Copies of this patent with color drawing(s)/photograph(s) will be provided by the Office upon request and payment of the necessary fee.

1. Bag

1.1 : Perspective

1.2 : Front

1.3 : Back

1.4 : Right

1.5 : Left

1.6 : Top

1.7 : Bottom

1.8 : Enlarged detail view taken from 1.1

1.9 : Perspective in Open Configuration

1.10 : Enlarged detail view taken from 1.9

The characteristic features of the design lie in the combination of the shape and decorative rings of three different colors on the sides of the bag; protection for color is claimed.

1 Claim, 10 Drawing Sheets
(9 of 10 Drawing Sheet(s) Filed in Color)
